United States Patent Office

Des. 232,638
Patented Sept. 3, 1974

232,638

LAVATORY

John W. Mather, 2635 Washington Mill Road,
Bellbrook, Ohio 45305

Filed Mar. 20, 1973, Ser. No. 342,989

Term of patent 14 years

Int. Cl. D23—02

U.S. Cl. D23—58

Fig. 1

Fig. 2

FIG. 1 is a top plan view of a lavatory showing my new design;

FIG. 2 is a bottom plan view thereof;
 FIG. 3 is a front elevational view thereof;
 FIG. 4 is a rear elevational view thereof;
 FIG. 5 is a right side elevational view thereof;
 FIG. 6 is a left side elevational view thereof; and
 FIG. 7 is an enlarged fragmentary view of the soap-holding portion thereof.

I claim:

The ornamental design for a lavatory, as shown.
